UNITED STATES PATENT OFFICE.

WILLIAM G. KENDALL, OF NEWARK, NEW JERSEY.

PARTITION FOR VANITY CASES.

Application filed June 29, 1920. Serial No. 392,852.

To all whom it may concern:

Be it known that I, WILLIAM G. KENDALL, a citizen of the United States, residing at Newark, in the county of Essex and State of New Jersey, have invented certain new and useful Improvements in Partitions for Vanity Cases, of which the following is a specification.

This invention relates to improvements in vanity cases and more particularly to a novel partition member for such cases.

The invention is especially designed for employment in connection with vanity cases which are designed to hold two compressed powder tablets, one of which may for example be of rouge and the other of face powder, each tablet being provided with an individual powder puff and the partition member being designed to separate the tablets or pads as well as their puffs, and one of the primary objects of the invention is to so construct the partition member that the same may be readily stamped or otherwise formed from sheet metal, may be readily disposed within the case and removed therefrom when required and which will be inconspicuous and yet retain the pads or tablets and their respective puffs separated so that powder from one tablet cannot become comingled with powder from the other tablet.

Another object of the invention is to so construct the partition member that when the same is in place within the case, it will not only serve as a partitioning means but also as a means for defining separate compartments within the case within which compartments may be individually placed the compressed powder tablets or pads and their respective puffs, these compartments being of a general contour to conform to the shape of the said tablets and puffs.

It is a further object of the invention to so construct the body of the case and the partition member of the present invention that when the member is disposed within the said body it will be securely held against accidental displacement although it may be readily removed whenever required.

50 In the accompanying drawing:

Figure 1 is a top plan view of a vanity case provided with a partitioning member constructed in accordance with the present invention;

55 Fig. 2 is a vertical front to rear sectional view on the line 2-2 of Fig. 1.

Fig. 3 is a perspective view of the partitioning member;

Fig. 3 is a vertical longitudinal sectional view through a vanity case provided with a modified form of partition;

Fig. 5 is a perspective view illustrating the modified form of partitioning member.

In the drawings the body of the vanity case is indicated in general by the numeral 1 and the said body comprises a front wall 2, a rear wall 3, and end walls 4 which connect the front and rear walls along curved lines conforming generally to the contour of the compressed powder tablets 70 which are to be arranged within the said body of the case. The said body also includes a bottom which is indicated by the numeral 5. The lid of the case, indicated in general by the numeral 6, comprises a top 75 7, a front wall 8, a rear wall 9, and end walls 10, these walls being arranged in the same manner as the corresponding walls of the body of the case, and the said lid being so proportioned that when in closed position 80 it will fit over the open top of the said body. By reference to Fig. 2 of the drawing it will be observed that the upper edge portion of the walls 2 and 3 is struck in or offset inwardly as indicated by the numeral 11 so 85 as to adapt the outer surfaces of the walls of the lid to lie flush with the outer surfaces of the walls of the body and also so as to provide shoulders 12 extending along the upper portions of the walls 2 and 3 within 90 the body. The purpose of these shoulders will presently be explained.

The compressed powder tablets which are to be positioned within the body of the case are indicated in general by the numeral 13 95 and each is of circular marginal contour and of any desired construction. In connection with each of the powder tablets or pads there is associated a powder puff indicated by the numeral 14.

100 The partition member embodying the present invention is designed to be disposed within the body of the case in such a manner as to define within the case two compartments indicated by the numeral 15, in which 105 compartments the compressed powder tablets or pads with their respective puffs are to be housed in the manner clearly shown in Figs. 1 and 2 of the drawings. This partition comprises two members which are 110 formed of metal which may or may not be resilient as found expedient. The partition

is indicated in general by the numeral 16 and each member is indicated by the numeral 17. Each of the said members 17 is of substantially semi-annular form and the two members 5 are disposed with the intermediate portions of their convex sides in contact and are permanently secured together by stamping out from one of the members a tongue 18 which is fitted through a slot 19 in the other 10 member and then bent downwardly as clearly shown in Fig. 3 of the drawings, for the purpose stated. Thus the partitions may be said to consist of two article embracing members having their embracing sides presented in opposite directions, and inasmuch 15 as the compressed powder pads or tablets are of circular marginal contour, the members 17 will be adapted to more or less snugly embrace a side of their respective pads or 20 tablets, the other side of the tablets being embraced or substantially embraced by the adjacent end walls of the body of the vanity case in the manner clearly shown in Fig. 1 of the drawings. In assembling the partition 25 with the body of the vanity case, the partition is disposed within the case with the article embracing sides of the said members 17 presented toward or confronting the end wall of the said body of the case and 30 the said members 17 are preferably although not necessarily so proportioned that their end portions will engage against the front and rear walls of the body of the case. In any event these members, in conjunction 35 with the end walls of the said body will define compartments within the body in which may be disposed and housed the compressed powder tablets and their respective puffs.

It will probably be found desirable to provide 40 against accidental displacement of the partition within or the dropping of the same from the vanity case, and this result I accomplish in a very simple manner by forming incisions 20 in the upper corners of 45 each of the members 17 and slightly overturning the material below the incisions as indicated by the numeral 21. The incisions extend parallel to the upper edge of the member in which they are formed and by 50 turning out the extremities of the members below the incisions, I provide shoulders 22 which are designed to engage beneath the shoulders 12 when the partition is disposed within the body of the vanity case, as clearly 55 shown in Fig. 2 of the drawings. In this manner the partition is effectually locked within the case when disposed in position and yet it is not permanently secured but may be removed at any time by slightly flexing 60 the end portions of the members 17 toward each other.

As previously stated, the members 17 comprising the partition may or may not be formed of resilient metal. There are advantages 65 to be gained by employing resil-

ient metal but its use is by no means essential.

In the form of the invention illustrated in Figs. 4 and 5 of the drawings, the vanity case is indicated in general by the numeral 70 23 and the same includes a bottom 24. The case does not differ in fact from the case previously described but within the same I arrange a partition member such as the member shown in Fig. 5. 75

The partition member in this form of the invention is formed from a sheet metal blank folded medially so as to provide an upstanding partition portion or wall 25 comprising portions 26 which either lie in contact or which are slightly spaced, as found desirable, and each of these portions 26 is provided at its lower edge with an outstanding base portion 27. In assembling the partition with the case, the former is disposed within the latter with the base portions 27 resting upon the upper side of the bottom 24 of the case, the wall 25 serving to medially divide the interior of the case into the two compartments within which are to be arranged the compressed powder tablets or pads which in this form are indicated by the numeral 28. The base portions 27 are preferably cut away substantially on the arc of a circle as indicated by the numeral 29, so as to accommodate the adjacent sides of the bases of the respective pads 28. 90

In order that the pads 28 may be retained within the case, a disk 30 of paper or other suitable material is secured by adhesive as 100 at 31 to the upper side of the bottom 24 of the case within each of the compartments provided by the partition member, and secured by adhesive as at 32 to the upper side of each of the paper disks 30 is the base 105 of the respective pad or tablet 28.

Having thus described the invention, what is claimed as new is:

1. The combination with a vanity case, of a partition for the same comprising resilient 110 article embracing members each of substantially semiannular form, the said members being disposed together with their convex sides in contact and united to each other and having their concave sides presented in 115 opposite directions and toward the ends of the said case.

2. The combination with a vanity case having a shoulder formed interiorly upon opposite walls, of a partition for the interior 120 of the case comprising an article embracing member having an embracing side to confront one wall of the case and having its end portions deflected outwardly to provide shoulders engageable beneath the first mentioned shoulders. 125

In testimony whereof I affix my signature.

WILLIAM G. KENDALL. [L.S.]
